PERMANENT WAVE APPARATUS AND
METHOD

Paul C. Rilling, Minneapolis, Minn., assignor to
Rilling-Arnau Company, Minneapolis, Minn., a
corporation of Minnesota

Application June 14, 1935, Serial No. 26,601

7 Claims. (Cl. 132—36)

This invention relates to the art of producing waves upon human hair and more particularly to the production of the so-called "permanent waves" upon the hair of a human head.

5 My invention has for an object the provision of a simple and highly efficient apparatus for effecting "permanent waves" of a more perfect and natural form than heretofore have been produced and with less discomfort to the subject.

10 Another object of my invention is the provision of simple and economical apparatus for permanent waving which will permit of the "Croquignole" type wherein an efficient clamping device is provided for gripping a flat lock of hair and 15 cooperates with the curling rod, heater and pad which are associated therewith and which furthermore provides a means for permitting the spreading and arrangement of the individual hairs after the clamp has been initially applied 20 to produce the most efficient results and which, after re-arrangement, may be locked or clamped in its second stage firmly upon the lock of hair thereby securely gripping all of the hairs and 25 clamping the same together to prevent displacement and individual pulling of the hairs.

It is a further object to provide apparatus of the class described which will prevent unequal strains being imposed upon the several individual hairs of a lock, equalizing said strains and preventing what is termed in the beauty art as "pull 30 burn".

More specifically, it is an object, in conjunction with efficient heating mechanism and curling rods, to provide a two-stage clamp adapted to uniformly 35 grip a flat lock of hair in such manner that in one locked position of the clamp the individual hairs may be spread or arranged as desired with the clamp applied and in the second locked stage the hairs will be securely clamped together in a uniform manner.

A further object is the provision of a clamp provided with aprons at the sides of the protector for deflecting steam discharge outwardly and upwardly and preventing impingement thereof 45 against the scalp.

Still another object is the provision of a protector for the clamp of compressible, resilient nature which when the clamp is properly applied 50 causes a uniform tension to be placed upon the individual hairs and closely cooperates with the first stage clamping action to automatically equalize strains upon the hairs of the scalp.

A further object is the provision of a new and 55 improved method of waving hair which is highly

effective in results and facilitates handling and waving of the hair on a human head.

These and other objects and advantages of the invention will be more fully set forth in the following description made in connection with the accompanying drawing, in which like reference characters refer to similar parts throughout the several views, and in which:—

Fig. 1 is a side elevation of an embodiment of my apparatus assembled and shown in operative 10 position on a lock of human hair;

Fig. 2 is an end elevation of the same;

Fig. 3 is a vertical section, on a somewhat larger scale, taken approximately on the line 15 3—3 of Fig. 1;

Fig. 4 is a plan view showing my improved protector clamp applied in the first clamping stage to a flat lock of hair;

Fig. 5 is a similar plan view showing the clamp 20 in the second locking stage;

Fig. 6 is a detail view showing the manner in which a suitable embodiment of curling rod is applied to the outer end of the lock of hair for spiral winding thereof, and

Fig. 7 is a cross section of a somewhat different 25 form of protector pad incorporated in connection with the clamp.

In the embodiment of the invention illustrated, I provide a clamping device indicated as an entirety by the letter C, a winding rod R adapted 30 for detachable mounting upon said clamp, and a heater assembly H adapted to grip a lock of hair wound upon said rod and be connected thereby with the rod and clamp.

The clamp C, as shown, comprises a pair of 35 clamping bars 10 and 11, respectively, of opposed channel construction hinged together as shown at their right hand ends by means of a small up-standing bracket 12 having an attachment base or flange 12a which is pivoted by a rivet 13 to clamping bar 11. Clamping bar 11 has mounted therein as clearly shown in Fig. 4, a compressible 40 clamping pad 14 which is detachably held in a grooved holder 8 pivoted intermediate its ends (and, as shown, at a point nearer the right hand 45 end), to the channel clamping bar 11. The clamping pad is thus swingably adjustable through short angulation relative to the clamping bar 11 for a purpose later to be described. A leaf spring 9, in much the shape of a hair pin, is interposed 50 between holder 8 and the back of channel shaped clamping bar 11, urging the left hand end of the clamping pad outwardly. Clamping pad 14, as shown, is integrally formed with a protector pad 14a which extends below clamping bar 55

11 and is made of compressible material, such as sponge rubber, and as shown carries a series of depending and staggered lugs 14b for engagement with the scalp of the subject. The clamping surface of pad 14 is defined by a straight relatively wide edge extending from the upper surface of the clamping pad portion to the lower portion of the protector pad 14a. A flexible and relatively thin apron 14c is integrally formed, as shown, with 5 the clamping pad and protector, and extends outwardly some distance beyond the longitudinal outer edge of clamping bar 14, and also some distance beyond the ends of said bar.

Clamping bar 10 is provided with an integrally 15 constructed compressible pad similar to the pad 14 having the upper clamping portion 15 which is seated in the channel of bar 10 and having the protector portion 15a, the depending teats or lugs 15b for engagement with the scalp and the apron 15c of similar construction to the apron 14c. The clamping edges of the two pads 14 and 15 are substantially flat and are opposed.

The left hand ends of clamping bars 10 and 11 are provided with a two-stage clamping lock 25 comprising a hinged plate 16 one end of which is pivoted to the left hand end of clamping bar 10 and which forms a part of an upstanding bracket 16a for receiving an end of the winding rod. The locking plate 16 carries at its free end a bell crank tightening lever 17 provided with a projecting pin 17a at its shorter end, which pin extends beyond both the upper and lower surfaces of lever 17 for engagement with the left hand bifurcated end of clamping bar 11 which is 30 formed with pin-receiving hooks 11a. Said pin works in an arcuate slot 16b formed in the plate 16. In the position shown in Fig. 4 the clamping device is retained or locked in the first stage position, clamping bar 11 having been pushed inwardly by finger pressure at its free end and the pin 17a engaged in the hook shaped retaining portions 11a. In Fig. 5 the lock is shown in second stage or tight clamping position, the lever 17 having been swung toward the outer longitudinal side of clamping plate 11 beyond dead center 35 position.

Winding rod R is of more or less conventional construction being tapered inwardly rather sharply from both the outer ends of the spool 19 50 and having a hair retaining clip 20 hinged to the right hand end thereof and conformed to fit the tapered shape of the spool and with a wide central portion 20a for engaging the end of a lock. A knob or handle 21 is fixed to the right hand 55 end of the rod and a squared connection element 22 is connected with the left hand end, provision being made for the turning of spool 20 relative to member 22 in one direction, while being prevented from turning in the opposite direction. The squared end 22 of the winding rod may be 60 non-rotatively engaged with a slot in the upper end of the bracket 16a, while the diminished cylindrical portion 21a at the right hand end of the rod may be rotatively engaged in the slot located in the upper end of bracket 12.

My improved heater unit includes a longitudinal body member 24 which may, if desired, be constructed of bakelite or other dielectric material having embedded or positioned therein 65 a suitable heating element 25 which element extends longitudinally of member 24 from points adjacent the ends thereof. Body 24 is encased by a metal shell or casing 26 having hinge elements 26a integrally formed therewith and disposed at 70 each of the sides thereof. Casing 26 is con-

structed from heat conductive metal, such as aluminum and the under surface is electro-plated or coated with dark pigment material, preferably black in color applied in such a way as to produce a dull finish rather than a glazed finish. I have discovered that by electro-plating or 5 coating the under surface of casing 26 in such manner, the transmission of heat and radiation of heat or emissivity of heat from the bottom of the casing 26 is very materially improved. An 10 electro-plating method known to the trade as "alumilite" has been very successfully utilized in the construction of my heater unit. Emissivity has been increased from that obtained from the plain metal of approximately 15% to 20% to 15 80% to 90% when the under surface of the casing 26 is so treated. This enables, in my device, heating elements of much less wattage to be used, making a reduction of substantially 35% in the wattage of the heating element, with, of course, the attendant saving of current on the plurality of heating units used in one permanent wave machine.

The body forms the top or upper portion of the heating chamber and a pair of elongated 25 segmental sides 27 of the length of body 24 are hinged to the side edges thereof completing the heating chamber. Sides 27 may be in the form of metal plates or arcuate cross section, as shown in Fig. 3, having flanged ends 27a of substantially horn shape which cooperate with the sector shaped flanges 26b of the shell 26 to restrict the openings at the ends of the heating chamber, the openings defined by flanges 27a and 26b being substantially circular when the 30 hinged sides are closed and disposed eccentrically 35 of the exterior periphery of the heating chamber.

A pair of upstanding posts 28 are secured by suitable means to the top of shell 26, one being disposed adjacent each end thereof and are of split construction made from insulating material to receive the electrical service wires 29 which pass therethrough and are electrically connected with the heating element 25. The upper portions of posts 28 are connected by a rod 30 having mounted thereon a spacing sleeve 31 and a hinge pintle 32 extends between the upper extremities of said posts upon which are mounted a pair of cooperating actuating levers 33 disposed one on each side of the device and preferably constructed from insulating material and having finger grips 33a formed therein. A pair of upstanding arms 34 are secured to the medial portion of the external sides of heater sides 27, one for each of said sides, the upper portions of 50 which are off-set inwardly and terminate in outwardly curved ends 34a which are engaged beneath the finger grip levers 33. A bent spring 35 of substantially hair-pin shape has its medial portion looped to surround hinge pintle 32 and 55 the free ends thereof urge arms 34 and consequently finger grip levers 33 in outward directions thereby normally holding the sides 27 of the heater inwardly as shown in Figs. 2 and 3.

Operation

In effecting a so-called "permanent wave" with my improved apparatus, a lock of hair is first divided from the head of hair, combed into flat form and the clamping device C is then applied with the protector pad in contact with the scalp. In initially applying the clamping device the operator presses the same against the scalp with sufficient pressure to somewhat compress the protector pad while she forces the clamping bars 70 75

10 and 11 together by finger pressure securing the lock in the first stage position by engaging pin 17a with the hooks 11a disposed at the left hand end of clamping bar 11 as shown in Fig. 4. When 5 the clamp is so applied the cooperating clamping pads 14 and 15 will lightly engage the multiplicity of hairs constituting the lock and because of the pivotal connection of clamp pad holder 8 with clamping bar 11 the clamping surfaces of the 10 two clamping pads will be brought into parallel relationship.

When the clamping device is so initially applied and the operator's pressure of the device against the scalp released the elasticity and compressibility 15 of the material constituting protector pads 14a and 15a causes the clamp to move outwardly slightly from the scalp thereby putting uniform tension on all of the individual hairs.

The operator next distributes and arranges the 20 individual hairs as uniformly and smoothly as possible within the clamping device, whereafter tightening lever 17 is swung to the secondary locking position as shown in Fig. 5 past dead center, locking the clamping elements tightly about 25 the re-arranged lock with adequate clamping pressure to prevent slippage or movement of the individual hairs relatively to the clamping pads.

The outer end of the lock of hair is then connected with the central portion of the winding 30 rod R, the extremity of said lock being disposed between the retaining clip 20 and the rod and the winding of the hair is then performed in spiral fashion on the rod, the convolutions of the lock 35 of hair over-lying one another successively and of course being of increasing width from the end of the lock toward the scalp.

The rod R with the lock of hair tightly wound thereon is next placed in the brackets 12 and 18a, the squared end 22 of the rod being disposed in 40 the enlarged slot of bracket 18a while the diminished cylindrical portion 21a at the opposite end of the rod is disposed for rotative movement in the slot of bracket 12. The lock of hair is further tightened or wound with the rod connected with 45 the clamping device by further turning of the handle or knob 21. A permanent wave pad or treating pad of conventional structure which contains suitable treating fluid is next wrapped about the wound lock and rod as shown in Fig. 3 in conventional manner, and the heating unit is then 50 clamped about the rod, lock and treating pad by first retracting the sides 27 of the heater by finger pressure of the finger gripping levers 33a, surrounding the enveloped wound lock with the 55 heating chamber and releasing the finger grips 33a.

It will be observed that due to the shape and 60 construction of the sides and body of the heater proper the cylindrical enveloped lock of hair is substantially enclosed, the end flange construction 65 of the heater chamber members engaging the enveloping pad and making escape of steam or entrance of air very slight. When all of the hair on the head desired to be waved is separated into locks and prepared in the manner described with reference to the first lock, the electrical 70 heating circuits through the several heating elements are closed and heat is applied in conventional manner for the requisite time and the apparatus is removed.

During the heating period the subject is avoided 75 considerable discomfort due to the outwardly protruding aprons 14c and 15c on the clamping device which deflect any currents or radiated heat

from the heater proper. "Pull burn" is avoided during the employment of my apparatus since the individual hairs are uniformly tensioned and since there are a multiplicity of such hairs in each lock and pulling tension is uniform and very 5 slight on each individual hair and is equalized through the elasticity and compressibility of the protector pad and through the distribution of the hairs and equalization of strains at the time the arrangement of the individual hairs is made 10 with the clamping device loosely locked in the first stage.

From the foregoing description it will be seen that my improved method of waving hair upon a human head constitutes, generally speaking, in 15 dividing off from the head of hair a flat lock, initially gripping that lock disposed flat-wise with a clamp disposed adjacent the scalp and exerting only sufficient gripping force to retain the clamp 20 to the lock and maintain the arrangement of individual hairs; then re-arranging and distributing the individual hairs uniformly while the same are initially gripped and thereafter securing the clamp in the second locking stage to tightly grip 25 the re-arranged hairs; then winding the lock from its end to a point near the clamp upon a rod and applying the hair treating solution and heating the wound hair with a suitable means, such as the improved heater unit construction disclosed 30 herein.

Extensive actual use has shown that highly improved results in producing a natural waviness of the hair through so-called "permanent waves" have been effected by my improved apparatus and 35 my improved method. "Pull burn" is avoided, the scalp is protected from uncomfortable heat and no separate guard or scalp pad is required. It will further be noted that the protector pad and clamping pad members integrally formed 40 can be removed for sterilization or cleaning.

In Fig. 7 I illustrate a somewhat different form of protector pad which I really prefer in most instances to the specific form disclosed in Figs. 1 to 6. This form of pad is identical 45 with the form first disclosed, with the following exceptions: The staggered lugs or teats 14b of the first form are eliminated and in place thereof a pair of soft, elastic, preferably sponge rubber protector pads 37 are cemented or otherwise secured to the under side of the pad portions 14a extending the full length of the pad and having preferably beveled sides as clearly 50 shown in Fig. 7. The inner and opposed sides of the sponge rubber pads 37 being rather sharply beveled form a converging entrance for the 55 hairs and facilitate arrangement of the individual hairs within the clamping device when the lock is in the initial or first stage. As in the form previously described, when the clamping device is initially applied to a flat lock of hair, the operator in locking the device in the first stage or initial position presses the protector pad somewhat against the scalp while holding the 60 lock of hair slightly tensioned and upon initial locking and release of the clamping device the resiliency of the pads 37 causes the clamping devices to slip upwardly slightly, equalizing the strains and tension on the individual hairs and of course on the scalp.

It will, of course, be understood that various 70 changes may be made in the form, details, arrangement and proportions of the parts, without departing from the scope of my invention, which, generally stated, consists in a device capable of 75

carrying out the objects above set forth, and in the novel parts and combinations of parts disclosed and defined in the appended claims.

What is claimed is:—

- 5 1. The method of waving hair upon a human head which consists in dividing off from the head of hair a flat lock, initially gripping said lock with a flat clamp adjacent the scalp and in so doing exerting only sufficient gripping force to retain the clamp to the lock of hair and maintain the arrangement of individual hairs in said lock, re-arranging and distributing the individual hairs uniformly while the same are initially gripped, then securing said clamp to tightly grip the re-arranged hairs, winding said lock from its end to a point near said clamp upon a rod and treating the wound hair with heat and hair-softening moisture.
- 10 2. The steps in the method of waving hair on a human head which consist in dividing off from the head of hair a flat lock, initially clamping said lock adjacent the scalp and in so doing exerting only sufficient gripping force to maintain the individual hairs in said flat lock arrangement permissive of re-arrangement, re-arranging and distributing the individual hairs while said lock is gripped and tightly gripping the re-arranged lock of hair adjacent the scalp preparatory to winding said lock.
- 15 3. In a clamping device for permanent hair waving, a pair of clamping bars having hinged relation adjacent one end of said device and being separable for insertion of a flat lock of hair at the opposite end of the device, means for securing said bars together in substantially parallel relation and in two different predetermined positions to exert two different degrees of clamping pressure on the same lock of hair and a protector pad beneath each of said bars and connected therewith, said protector pads being constructed of highly compressible and elastic material for urging said bars upwardly from the scalp when the device has been applied with some pressure exerted in the direction of the scalp.
- 20 4. In permanent hair waving apparatus a pair of clamping bars having hinged relation, cooperating clamping pads carried by said bars in opposed relation, means for securing said bars together in two different predetermined relations and to exert two different degrees of clamp-

ing pressure on the same lock of hair, one of said clamping pads being swingably mounted on the bar with which it is connected whereby the clamping surfaces of the opposed pads may be disposed in precise parallel relationship in both of said predetermined, secured positions of said bars.

5. The structure set forth in claim 4 and resilient means for urging the end of said swingable clamping pad adjacent the unhinged ends of said bars outwardly.

6. In a clamping device for permanent hair waving a pair of clamping bars having hinged relation adjacent one end of said device and being separable with the other end of the device for insertion of a flat lock of hair, means for locking said bars together in substantially parallel relation and in two different predetermined positions to exert two different degrees of clamping pressure on the same lock of hair, cooperating clamping pads carried by said bars in opposed relation, one of said clamping pads being mounted in this bar for limited swinging movement relative thereto whereby precise parallel relationship of the opposed clamping edges of said pads may be obtained in both of said locked positions of said bar and depending protector elements secured to the undersides of said bars and constructed of highly compressible and elastic material to urge the device upwardly from the scalp when said pads are compressed against said scalp and thereby tensioned.

7. The method of waving hair upon a human head which consists in dividing off from the head of hair a flat lock, initially gripping said lock with a flat clamp disposed against the scalp and in so doing exerting only sufficient gripping force to retain the clamp to the lock of hair and to maintain the arrangement of individual hairs in said lock, applying resiliently, light upward pressure upon said clamp and lock in a direction away from the scalp during said initialled gripping and thereby equalizing the strains and tension on the individual hairs of said lock, then securing said clamp to tightly grip the hairs of said lock, winding said lock from its end to a point near said clamp upon a rod and treating the wound hair with heat.
